UNITED STATES PATENT OFFICE.

SYLVANY M. ROUSE, OF NEW ORLEANS, LOUISIANA.

DESIGN FOR A PACK OF PLAYING-CARDS.

42,237.

Specification for Design.

Patented Feb. 27, 1912.

Application filed November 18, 1911. Serial No. 661,172. Term of patent 7 years.

To all whom it may concern:

Be it known that I, SYLVANY M. ROUSE, a citizen of the United States, residing at New Orleans, in the parish of Orleans and State of Louisiana, have invented a new, original, and ornamental Design for Packs of Playing-Cards, of which the following is a specification, reference being had to the accompanying drawings, forming parts thereof.

The drawings show the various cards contained in the pack and illustrate my new design.

I claim:

The ornamental design for a pack of playing cards as shown.

SYLVANY M. ROUSE.

Witnesses:

VERONICA E. ROUSE,
M. A. BLOUIN.
